UNITED STATES PATENT OFFICE.

WILLIAM E. FITCH, OF LOUISVILLE, KENTUCKY.

FIREPLACE-GRADE.

SPECIFICATION forming part of Letters Patent No. 552,282, dated December 31, 1895.

Application filed August 18, 1893. Serial No. 483,466. (No model.)

To all whom it may concern:

Be it known that I, WILLIAM E. FITCH, a citizen of the United States, residing at Louisville, in the county of Jefferson and State of Kentucky, have invented a certain new and useful Improvement in Portable Fireplaces, of which the following is a full, clear, and exact description.

This invention relates to that class of portable fireplaces which comprise a back or lining and a grate proper, and the object of my invention is twofold, namely—first, to supply such fireplaces with a basket front by which the fire may be controlled or regulated and by which also the ashes may be kept within the fireplace—that is to say, may be prevented from falling out into the room—and, second, to provide for such fireplaces what is known in the trade as a “summer front,” by means of which the fireplace may be closed up and be given a presentable appearance when not in use.

Having thus stated the principle of my invention, I will proceed now to set forth the best mode in which I have contemplated applying that principle, and then will particularly point out and distinctly claim the part, improvement or combination which I claim as my invention.

In the accompanying drawings, illustrating my invention, in the several figures of which like parts are similarly designated, Figure 1 is a front elevation. Fig. 2 is a vertical cross-section taken in the plane of line 2 2, Fig. 1. Fig. 3 is a vertical cross-section, on a larger scale, of the double-basket front and its connections; and Fig. 4 is a similar view of a modification. Fig. 4^a is a horizontal section on line 4, Fig. 4, of one end of the double-basket front; and Fig. 5 is a vertical cross-section taken in the plane of line 5 5, Fig. 1.

The back or lining herein shown is composed of the rear wall *a* and side walls *b*, which are made with the rabbet or molding *c* to receive the fire-brick or tile *d*, and these walls are also adapted to receive and support the grate *e*, which may be of any approved construction. This back or lining is also supplied with a top *f*, which is provided with dampers *g* and *h*, one of which, as *g*, may be made of a fixed grid and a sliding grid movable above or upon the fixed grid, like a com-

mon stove-damper, and either or both of which may be hinged to the top so as to be capable of being turned up, as in Fig. 5. I do not 55 limit my invention, however, to a top having a damper or dampers, and yet I prefer to employ dampers at that point for obtaining the best results in starting and maintaining the fire. The facing is composed of the pilasters *i i* and hooded cross-piece *k*, made in three, more or less, pieces and suitably secured to the back.

The basket or front of the grate is composed of a grid *l* having rearwardly-projecting hooks 65 *m*, which enter slots *n* in the molding *c* and engage the edges of such slots to hold such grid in position to confine the fuel.

o is a grid having the movable grid *o'* fitted to it to form a damper. This grid *o* is made 70 with the rearwardly-turned top *o²*, which overlaps the grid *l*. The grid *o* is secured to the grid *l* by buttons or other fastenings *o³* at the top and by resting against one or more projections *o⁴* at the bottom of grid *l*. It will be 75 observed that the grids *l* and *o* are separated from one another by a considerable space *p*, and into this space fall the ashes and cinders which escape through the grid *l*. The grids *l* and *o o'* constitute what I call the “double- 80 basket” front with damper. Below the damper composed of the grids *o* and *o'* I arrange the base-damper, ash-guard or crown-piece *r*, which may be composed of a suitable fixed grid and a sliding grid. This base-damper is 85 of suitable configuration or design to make a pleasing finish, and in the preferred form its sides overlap the pilasters *i i*, as seen in Fig. 1. The lower edge of the double-basket front rests upon or meets the upper edge of the 90 base-damper, and between and beyond them projects the shaker-socket *s*. The ashes and cinders falling through space *p* are concealed by and confined behind the base-damper.

The “summer front” *t*, so called, as above 95 stated, is a casting of ornamental construction and adapted to be fitted and held between the hooded cross-piece *k* and the top of the double-basket front, and for this purpose said summer front may be made longer than the 100 opening above the double-basket front so as to be slipped up behind and within the frame until its hook *t'* is free to be passed behind the inner edge of the double-basket front, when

it is dropped down upon the upper edge of such front. Lugs u projecting inwardly from the pilasters support the summer front from falling in. (See dotted lines, Fig. 1 and 5 in Figs. 2 and 5.) In Figs. 4 and 4^a I have shown the double-basket front having the grid l provided with the outwardly-turned top o^2 instead of having an inwardly-turned top on the grid o , and I have shown said grid o secured to grid l by screw-bolts v fitted to sockets w on grid l . In Fig. 4^a the return end o^x of the grid o is shown in detail, as is also the screw-bolt v .

The base and double-basket-front dampers 15 in connection with the chimney-flue connection, whatever it may be, whether a simple opening in the back or the dampers shown in the drawings, make it possible to control the fire very perfectly and to maintain a fire for 20 a considerable length of time. Moreover, the ash-guard and the double-basket front confine the ashes and cinders within the fireplace and concealed from view. In addition to these practically useful functions, the ash- 25 guard and double-basket front and the summer front add materially to the appearance and finish of the article.

What I claim is—

1. A portable fire-place having a double 30 basket front provided with a damper, and a grate having a front grid to which the double

basket front is secured, substantially as described.

2. In a portable fire-place, a double basket front, composed of a grate and a grid therefor 35 to confine the fuel, and a damper-grid secured to and in front of such first-named grid and separated therefrom by a space sufficient to permit the escape of ashes and cinders, substantially as described. 40

3. In a portable fire-place, a double basket front composed of a grate and a grid therefor 45 to confine the fuel and a damper-grid secured to and in front of such first-named grid, and separated therefrom by an ash and cinder space, and a top extending between the fuel grid and the damper-grid to cover such space, substantially as described.

4. As an improved article of manufacture, a portable fire-place composed essentially of 50 a double basket front having a damper, an ash-guard or base-damper, a facing, a summer front confined between such basket damper and facing, a grate and a lining or back, substantially as described. 55

In testimony whereof I have hereunto set my hand this 15th day of August, A. D. 1893.

WILLIAM E. FITCH.
